UNITED STATES PATENT OFFICE

JOHN NICOL, OF DETROIT, MICHIGAN, ASSIGNOR TO CONTINENTAL-DIVCO COMPANY, OF DETROIT, MICHIGAN, A CORPORATION OF MICHIGAN

DESIGN FOR A HOUSE-TO-HOUSE DELIVERY VEHICLE BODY

Application filed December 9, 1932. Serial No. 46,409. Term of patent 14 years.

To all whom it may concern:

Be it known that I, JOHN NICOL, a citizen of the United States of America, residing at Detroit, in the county of Wayne and State of Michigan, have invented a new, original, and ornamental Design for a House-to-House Delivery Vehicle Body, of which the following is a specification, reference being had to the accompanying drawing, forming part thereof.

Fig. 1 is a side elevational view of my new body design showing the door in closed position,

Fig. 2 is a front elevational view thereof, Fig. 3 is a plan view thereof, and Fig. 4 is a side elevational view of the body as seen from the side opposite to Fig. 1, the door being open.

What I claim as my invention is:

The ornamental design for a house-to-house delivery vehicle body, substantially as shown.

In testimony whereof, I affix my signature.

JOHN NICOL.
